[57] CLAIM

The ornamental design for a watch, as shown and described.

DESCRIPTION

FIG. 1 is a top view of my new watch design, showing the wristwatch disposed in a position it would be when worn; FIG. 2 is a bottom view thereof;

FIG. 3 is a right side view thereof;

FIG. 4 is a right side view thereof;

FIG. 5 is a right top perspective view thereof;

FIG. 6 is a top view of my new watch design disposed in a flattened state;

FIG. 7 is a bottom view thereof;

FIG. 8 is a right side view thereof;

FIG. 9 is a left side view thereof; and,

FIG. 10 is a perspective view thereof.
